UNITED STATES PATENT OFFICE.

HIRAM A. SMITH, OF PAW PAW, MICHIGAN.

WALL STRUCTURE.

1,250,686.

Specification of Letters Patent. Patented Dec. 18, 1917.

Application filed February 2, 1917. Serial No. 146,110.

To all whom it may concern:

Be it known that I HIRAM A. SMITH, a citizen of the United States, residing at Paw Paw, county of Van Buren, State of Michigan, have invented certain new and useful Improvements in Wall Structures, of which the following is a specification.

This invention relates to improvements in wall structures.

10 The main objects of this invention are to provide an improved hooped wall structure in which the hoops are so disposed and connected as to effectively support all the staves or blocks of the wall.

15 Further objects, and objects relating to structural details, will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing, forming a 25 part of this specification, in which:

Figure I is a detail front elevation of a silo embodying the features of my invention.

Fig. II is a detail vertical section on a 30 line corresponding to line 2-2 of Figs. I and III.

Fig. III is a detail view, partially in section, on a line corresponding to line 3-3 of Figs. I and II.

35 Fig. IV is a perspective view of a pair of the lugs employed.

Fig. V is a perspective view of another type of lugs employed.

Fig. VI is a detail longitudinal section on 40 a line corresponding to line 6-6 of Fig. I.

In the drawing similar reference characters refer to similar parts throughout the several views, and the sectional views are taken looking in the direction of the little 45 arrows at the ends of the section lines.

In the erecting of my improved silo I lay the wall blocks 1 in tiers so as to provide door openings 2. The door blocks or cross members 3 extend across these door openings, the door blocks being laid in the wall with the wall blocks as the silo is erected. The wall is encircled by the hoops 4 disposed across the door blocks 3, as shown in Fig. I. These hoops 4 are provided with 55 adjusting lugs 5. The details of these lugs are not shown, as lugs suitable for the pur-

pose are known in the art. Between the hoops 4 are intermediate hoops 6. On the hoops 4 at each side of the door opening I mount the multiple lugs 7 having holes 8 therethrough for the hoops 4 and eyes 9 for the truss rods 10, which are disposed at one side of the hoops 4. The lugs 7 are also provided with outwardly diverging eyes 11 for the V-shaped tie rods 12. On these tie rods 12 I mount the attaching lugs 13 for the intermediate hoops 6. These attaching lugs have eyes 14 for the hoops and transverse eyes or holes 15 through which the tie rods are arranged. The lugs 7 are preferably provided with inwardly projecting wall engaging members 16, see Fig. II, which engage the wall between blocks thereof and prevent the lugs slipping up and down. The truss rods 10, tie rods 12, and the hoops 6 are 70 threaded at their ends to receive suitable nuts 17 by means of which they may be tightened to properly tension the same.

With this simple and very economical arrangement of parts I am enabled to support the wall blocks throughout and also properly support the door blocks. With the walls thus supported the blocks are not likely to become broken or distorted owing to unequal stresses, as they are securely 75 bound or hooped throughout, and the hooping connected to provide a connected support for the silo.

I have illustrated and described my improvements in a simple and practical embodiment thereof. I have not attempted to illustrate or describe various adaptations which might be desirable in the general application of my improvements, as I believe the disclosure made will enable those skilled in the art to which my invention relates to embody or adapt the same as conditions may require.

Having thus described my invention, what I claim as new and desire to secure by Letters Patent, is:

1. The combination with a wall comprising blocks laid to provide a door opening and door blocks extending across said opening, of hoops disposed across said door blocks, oppositely disposed pairs of lugs mounted on said hoops at the edges of the door opening and provided with inwardly projecting wall engaging members and with holes through which said hoops are arranged and central truss rod eyes and outwardly diverging tie rod eyes, intermediate hoops disposed be-

2
tween such hoops, V-shaped tie rods disposed in opposed pairs at the sides of the door opening and engaged with the said tie rod eyes of said lugs, attaching lugs on the ends 5 of said intermediate hoops disposed in the bights of said tie rods, said attaching lugs having eyes for said intermediate hoops and transverse holes through which said tie rods are arranged, and truss rods connecting said 10 pairs of lugs engaged in the said truss rod eyes thereof, the said tie rods, truss rods and intermediate hoops being threaded at their ends and provided with attaching nuts whereby they may be adjusted, said first 15 named hoops being provided with adjusting lugs.

2. The combination with a wall comprising blocks laid to provide a door opening and door blocks extending across said opening, 20 of hoops disposed across said door blocks, oppositely disposed pairs of lugs mounted on said hoops at the edges of the door opening and provided with holes through which said hoops are arranged and central truss 25 rod eyes and outwardly diverging tie rod eyes, intermediate hoops disposed between such hoops, V-shaped tie rods disposed in opposed pairs at the sides of the door opening and engaged with the said tie rod eyes 30 of said lugs, attaching lugs on the ends of said intermediate hoops disposed in the bights of said tie rods, said attaching lugs having eyes for said intermediate hoops and transverse holes through which said tie rods 35 are arranged, and truss rods connecting said pairs of lugs engaged in the said truss rod eyes thereof, the said tie rods, truss rods and intermediate hoops being threaded at their ends and provided with attaching nuts whereby they may be adjusted, said first 40 named hoops being provided with adjusting lugs.

3. The combination of a wall provided with a door opening and cross members extending across said opening, of hoops disposed across said cross members, lugs mounted on said hoops at the edges of the door opening and provided with inwardly projecting wall engaging members and with 45 truss rod and tie rod eyes, intermediate hoops disposed between such hoops, tie rods disposed at the sides of the door opening and engaged with the said tie rod eyes of said lugs, attaching lugs for said intermediate 50 hoops engaged with said tie rods, and truss rods connecting said pairs of lugs engaged

in the said truss rod eyes thereof, the said tie rods, truss rods and intermediate hoops being provided with adjusting nuts, said first named hoops being provided with adjusting lugs, 60

4. The combination of a wall provided with a door opening and cross members extending across said opening, of hoops disposed across said cross members, lugs mounted on said hoops at the edges of the door opening and provided with truss rod and tie rod eyes, intermediate hoops disposed between such hoops, tie rods disposed at the sides of the door opening and engaged with the said tie rod eyes of said lugs, attaching lugs for said intermediate hoops engaged with said tie rods, and truss rods connecting said pairs of lugs engaged in the said truss rod eyes thereof, the said tie rods, truss 70 rods and intermediate hoops being provided with adjusting nuts, said first named hoops being provided with adjusting lugs.

5. The combination of a wall provided with a door opening and cross members extending across said opening, of hoops disposed across said cross members, pairs of lugs mounted on said hoops at the edges of the door opening and provided with inwardly projecting wall engaging members, intermediate hoops disposed between such hoops, tie rods disposed at the sides of the door opening connected to said lugs, attaching lugs for said intermediate hoops engaged with said tie rods, and truss rods connecting said 80 pairs of lugs, said tie rods, truss rods and hoops being provided with adjusting means. 85

6. The combination of a wall provided with a door opening and cross members extending across said opening, of hoops disposed across said cross members, pairs of lugs mounted on said hoops at the edges of the door opening, intermediate hoops disposed between such hoops, tie rods disposed at the sides of the door opening and connected to said lugs, attaching lugs for said 90 intermediate hoops engaged with said tie rods, and truss rods connecting said pairs of lugs, said tie rods, truss rods and hoops being provided with adjusting means. 95

In witness whereof, I have hereunto set my hand and seal in the presence of two witnesses.

HIRAM A. SMITH. [L.S.]
